CLAIM

The ornamental design for a fishing troller/diver, as shown and described.

DESCRIPTION

FIG. 1 is an upper front perspective view of a fishing troller/diver per the present invention, said fishing troller/diver having a plurality of apertures (four are shown) for connecting a fishing line to the front edge of the vertical fin portion of this troller/diver and a plurality of apertures (four are shown) for connecting line leaders to the rear edge of the same vertical fin portion;

FIG. 2 is a front elevation view of the fishing troller/diver from FIG. 1;

FIG. 3 is a rear elevation view of the fishing troller/diver from FIGS. 1 and 2;

FIG. 4 is a top plan view of the same fishing troller/diver from FIGS. 1 through 3;

FIG. 5 is a bottom plan view of the same fishing troller/diver, or opposite view from that shown in FIG. 4; and

FIG. 6 is a right side view of the same fishing troller/diver;

FIG. 7 is a left side view of the same fishing troller/diver, or opposite view from that shown in FIG. 6; and,

FIG. 8 is a right side view showing an enlarged view of the fishing troller/diver of this invention schematically connected with dashed lines at the front end to a fishing line extending from a fishing boat (also shown in dashed lines) for dragging through the water, and connected with dashed lines to a line leader connected to a representative top aperture in the rear of the vertical pin portion of this fishing troller/diver, the fishing boat, fishing line and line leaders being depicted in dashed lines as they are not a part of this invention.
